O. B. SALISBURY

SHOE

Filed Sept. 12, 1921

INVENTOR

Orlando B. Salisbury

UNITED STATES PATENT OFFICE.

ORLANDO B. SALISBURY, OF BROOKLYN, NEW YORK.

SHOE.

Application filed September 12, 1921. Serial No. 499,927.

To all whom it may concern:

Be it known that I, ORLANDO B. SALISBURY, a citizen of the United States, and a resident of Brooklyn, in the county of Kings and State of New York, have invented certain new and useful Improvements in Shoes, of which the following is a specification, accompanied with drawings and letters of reference, as will enable those skilled in the particular art to make and use the same.

My invention relates to right and left shoes or footwear, the principal object being to prevent the abnormal turning of the large, second, and little toe toward the third and fourth toe causing hallux valgus, overlapping toes, bunions, blisters, corns, callosities, and embedded toe nails from childhood to old age. Another object of my invention is to prevent abduction and rolling over inward or pronation of the weakened foot. A further object of my invention is to provide a correct form for a flat-foot brace and stiffening for a weakened foot. Still another object of my invention is to prevent shortened or hammer toes. And still another object of my invention is to prevent holes in the big and little toe portion of stockings. Lastly, another object of my invention is to provide the normal room to straighten deformed toes with wedges or rolls of cotton in a day. To accomplish these objects my invention consists essentially of a toe portion having the inner and outer toe edges on a straight line with the deflecting sides of the metatarsal portion, particularly at the waist, before the turn of the extension in front toward the median line and the same depth along the edges as the thickness of the wearer's toes in the adducted position of the foot.

In the drawing, Figure 1, is a top view of my shoe, showing the toe portion; Fig. 2, is a bottom view of the same in relation to the toes; Fig. 3, is a front view of the same showing the thickness of the toe portion from side to side; and Fig. 4, is an inner view of the same showing the thickness of the large toe, metatarsal, heel, and foreleg portion.

My invention for a normal foot or one nearly so, when voluntarily adducted, is constructed of a heel portion A having a low and broad heel α of rubber or leather as shown in Figs. 2 and 4. It is very slightly concave on the inner side and straight on the outer

border at the mediotarsal or transverse joint b , b' . This heel portion is continued along the deflecting sides from the first 1' and fifth 5' tarsometatarsal joint to the first 1" and fifth 5" metatarsophalangeal joint 60 of the wearer forming the metatarsal portion B, of the shoe, as illustrated in Figs. 1 and 2. It is slightly concaved on the inner side, particularly at the waist f , and straight at the outer border e . The ad- 65 ducting forces are located on the inner side at said mediotarsal joint b and on the outer side at the calcaneum c of the heel and at said fifth 5" metatarsophalangeal joint as shown in Figs. 1 and 2. Around the back 70 of the heel portion from the inner side of said mediotarsal joint b to the outer side at said calcaneum c' and the middle two-thirds of the outer border e are two stiffenings g g' inserted between the lining h and 75 back of the upper as illustrated in Fig. 2. This metatarsal portion is continued along the deflecting sides from the first 1" and fifth 5" metatarsophalangeal joint to the end of the extension i i' forming the toe 80 portion C having the inner and outer toe edge on a straight line with the waist f f' and lower j or upper j' side of the heel before the turn of said extension i i' in front (about three-fourths of an inch) toward the 85 median line m or division of the longitudinal arch and third 3 and fourth 4 toe as shown in Fig. 2. Or on a straight line with the first 1 and fifth 5 metatarsal bone are the normal large 1 and little 5 toe bones before 90 the turn of the extension i i' in front toward the median line m as illustrated in Fig. 2. This extension is for extra room, the final push, and stubbing of the toes. By turning the normal toes upward the five 95 metatarsal bones are raised to the surface of the skin indicating the deflecting lines of all the toes. In this case the large toe projects out about three-eighths of an inch, while the little toe meets the outer border 100 one-eighth of an inch less naturally making the cross line x , y the widest part of the foot and shoe. The inner sole pattern p include the area covered by the non-weight bearing portion of the foot, indicated 105 by the seams and nails in Fig. 2. This toe portion has the same depth k k' , along the edges as the thickness of the wearer's toes as shown in Figs. 3 and 4. There is no spring or dorsal flexion of the front of the 110

shoe corresponding to the foot. Its sole *l* is flat from side to side in front. The sole has a little lateral extension to protect the uppers and if broader on the inner side hinders pronation. A steel spring or removable brace in the shank at the mediotarsal joint *b b'* helps maintain the shape of the shoe and foot. The toe cap *n*, is stitched with two rows, preferably without a toe case, to the vamp or golosh in front of the little toe *i* and across to the first toe joint *l'* of the big toe *l* as illustrated in Figs. 1 and 2. In front the quarters *s* are supplied with eyelets and hooks for the shoe laces. The above described shoe is ready made and made to order in different lengths and widths from leather, rubber, or cloth.

It is apparent that this invention is also applicable to boots, oxfords, slippers, sandals, and overshoes, and other similar footwear by extending or omitting a part or all of the quarters *s*.

In using my invention with the feet held parallel to each other the body weight falls upon the heel, then over to the outer border of the metatarsal portion and little toe and against the upper then across to the inner side of metatarsal portion and forward along the large toe, the heel raises, and the end of the big toe and extension gives the final motion to the step as observed by a worn sole. The normal foot reforms as soon as the weight is removed in walking.

I am aware of the narrow-toed shoe with the abducting forces at the outer side of the mediotarsal joint *b'* and on the inner side of the heel at the calcaneum *c* and first *l'* metatarsophalangeal joint and along the edges of the toe portion that cause abduction, hallux valgus, bunions, and embedded toe nails. I am aware of the so-called common sense broad-toed shoe with the deepest part often in the middle of the toe portion, that compress the toes less and usually holds the foot in a position of abduction. Also, I am aware of shoes in which the length from the heel to the distal end of the first metatarsal bone is longer and the fifth metatarsal bone shorter in the shoe than in the foot that cause abduction and compress the toes less. Lastly, I am aware of Letters Patent No. 984,506, dated Feb. 14, 1911 and other similar shoes having an inner straight line from the lower side of the heel along the toe edge to nearly the first toe joint *l'* or toe cap seam *n'* before the turn inward, and concave on the outer side at the mediotarsal joint *b'* pushing the foot over to the inner side into a position of abduction, and slightly convex at the outer border *e*, then turns toward the median line without sufficient extension for the toes, final push, and stubbing of the foot. These I do not claim.

Having described my invention, what I

do claim as new and wish to secure by Letters Patent, is:

1. A shoe or footwear consisting of a heel portion, a metatarsal portion, and a toe portion having the inner toe edge on a straight line with the deflected lower side of said heel portion before the turn of the extension in front toward the median line of the wearer's toes, substantially as shown and described. 75

2. A shoe or footwear consisting of a heel portion, a metatarsal portion, and a toe portion having the inner and outer toe edge on a straight line with the deflected lower sides of said heel portion before the turn 80 of the extension in front toward the median line of the wearer's toes, substantially as shown and described.

3. A shoe or footwear consisting of a heel portion, a metatarsal portion, and a toe portion having the inner and outer toe edge on a straight line with the deflected lower sides of said heel portion before the turn of the extension in front toward the median line and the same depth along the edges as the 90 thickness of the wearer's toes, substantially as shown and described. 85

4. A shoe or footwear consisting of a heel portion, a metatarsal portion having a straight outer border, and a toe portion 95 having the inner and outer toe edge on a straight line with the deflected lower sides of said heel portion before the turn of the extension in front toward the median line and the same depth along the edges as the 100 thickness of the wearer's toes, substantially as shown and described.

5. A shoe or footwear consisting of a heel portion having a straight outer border at the mediotarsal joint, a metatarsal portion 105 having a straight outer border and the abducting forces on the inner side at the mediotarsal joint and on the outer side at the calcaneum of the heel and at the fifth metatarsophalangeal joint, and a toe portion 110 having the inner and outer toe edge on a straight line with the deflected lower sides of said heel portion before the turn of the extension in front toward the median line and the same depth along the edges as the 115 thickness of the wearer's toes, substantially as shown and described.

6. A shoe or footwear consisting of a heel portion having a straight outer border at the mediotarsal joint, a metatarsal portion 120 having a straight outer border and the abducting forces on the inner side at the mediotarsal joint and on the outer side at the calcaneum of the heel and at the fifth metatarsophalangeal joint, and a toe portion 125 having the inner and outer toe edge on a straight line with the deflected upper sides of said heel portion before the turn of the extension in front toward the median line and the same depth along the edges as the 130

thickness of the wearer's toes, substantially as shown and described.

7. A shoe or footwear consisting of a heel portion having a straight outer border at the mediotarsal joint; a metatarsal portion having a straight outer border and the abducting forces on the inner side at the mediotarsal joint and on the outer side at the calcaneum of the heel and at the fifth metatarsophalangeal joint; and a toe portion having the inner and outer toe edge on a straight line with the deflected sides of said metatarsal portion, particularly at the waist, before the turn of the extension in front toward the median line, and the same depth along the edges as the thickness of the wearer's toes, substantially as shown and described.

8. A shoe or footwear consisting of a heel portion having a straight outer border at the mediotarsal joint, a stiffening around the back from the inner side of said mediotarsal joint to the outer side of the calcaneum, and a heel; a metatarsal portion having a straight outer border and the abducting forces on the inner side at said mediotarsal joint and on the outer side at said calcaneum and at the fifth metatarsophalangeal joint; and a toe portion having the inner and outer toe edge on a straight line with the deflected sides of said metatarsal portion, particularly at the waist, before the turn of the extension in front toward the median line, and the same depth along the edges as the thickness of the wearer's toes, substantially as shown and described.

9. A shoe or footwear consisting of a heel portion having a straight outer border at the mediotarsal joint, a stiffening around the

back from the inner side of said mediotarsal joint to the outer side of the calcaneum, and a heel; a metatarsal portion having a straight outer border, a stiffening at said outer border, and the abducting forces on the inner side of said mediotarsal joint and on the outer side of said calcaneum and at the fifth metatarsophalangeal joint; and a toe portion having the inner and outer toe edge on a straight line with the deflected sides of said metatarsal portion, particularly at the waist, before the turn of the extension in front toward the median line, and the same depth along the edges as the thickness of the wearer's toes, substantially as shown and described.

10. A shoe or footwear consisting of a heel portion having a straight outer border at the mediotarsal joint, a stiffening around the back from the inner side of said mediotarsal joint to the outer side of the calcaneum and a low heel; a metatarsal portion having a straight outer border, a stiffening at said outer border, and the abducting forces on the inner side of said mediotarsal joint and on the outer side of said calcaneum and at the fifth metatarsophalangeal joint; and a toe portion having the large and little toe bones on a straight line with the deflected first and fifth metatarsal bone before the turn of the extension in front toward the median line, and the same depth along the inner and outer edge as the thickness of the wearer's toes, substantially as shown and described.

Signed at Brooklyn, in the county of Kings, and State of New York this 10th day of September A. D. 1921.

ORLANDO B. SALISBURY.
